REFLECTOR BULB LAMP

Orrick H. Biggs, Beverly, and Stuart S. Davis,
Lynn, Mass., assignors to Hygrade Sylvania
Corporation, Salem, Mass., a corporation of
Massachusetts

Application April 18, 1939, Serial No. 268,580

1 Claim. (Cl. 176—16)

This invention relates to reflector lamps, and in particular to reflector lamps of the tubular type, with a reflector coating on the interior of the bulb.

An object of the invention is to provide such a lamp of rugged construction and of long life. A further object is to provide a lamp producing a beam of light free from objectionable shadows.

Features of the invention are a mount for the filament of such a lamp, and the combination of such mount with the proper reflecting surface and atmosphere inside the lamp bulb.

Other objects and advantages of the invention will be apparent from a consideration of the following description, taken in connection with the accompanying drawing, in which:

Figure 1 is a profile view, partly in section, of a lamp according to the invention, and

Figure 2 is an enlarged cross-sectional view of the same lamp.

In Figure 1, the tubular lamp bulb 1 has the reflecting coating 2 over a portion of its interior surface, and has the reentrant stem 12, projecting into the bulb at one end. The stem 12 terminates in the press 3 through which the lead-in wires, which also serve as supports for the ends of the filament 14, are sealed. A glass rod or arbor 5, extends out of the stem 12, a molybdenum wire 6 being sealed into the glass button 7 at the end of the arbor 5, to support the middle of the filament, around which one end of the wire 6 is curled loosely in a small loop 8. One of the lead wires 4, is shorter than the other lead wire 15, and curves outward from the press toward the reflector coating 2, but is bent back at its end in a direction away from the coating to support one end 9 of the filament 14. The lead-in wire 4 is preferably bent back before touching the coating 2, in order not to scratch the latter. The other lead-in wire 15 extends upward, its end being bent out toward the coating to support an end 10 of the filament. The filament is preferably of the coiled-coil type, to give a high efficiency when arranged with its axis straight and parallel to the axis of the tubular bulb. The lamp is preferably filled with argon gas at about 600 mm. of mercury pressure, to provide an atmosphere with which the coating 2 will not react and to increase the temperature at which the filament may be safely operated. The coating 2 is preferably an opaque smooth specular reflecting film of vacuum-vaporized aluminum, and may be covered with aluminum oxide.

The lead-in wire 15 will be directly in front of the filament and will cast a narrow shadow.

However, the shadow will be in the straight forward direction, and the light from the reflecting surface will be nearly all reflected in that direction, so that at a short distance from the lamp the shadow will not be noticeable. To reduce the shadow at short distances from the bulb, the bulb is preferably frosted slightly, so that the frost will be sufficient to smooth out any irregularities in the beam, but not sufficient to diffuse the light enough to spoil the narrowness of the beam. The bulb may be frosted over its entire interior surface before the metal coating is applied, and then the reflecting surface itself will be roughened slightly, which will also tend to diffuse the reflection slightly to avoid shadows.

The arbor 5 terminates in the glass button 7, at a point below the filament, that is at a point nearer to the stem than is the axially perpendicular plane containing the nearest end of the filament, thus not only providing a rugged mount, but also keeping the arbor and button out of the path of the direct light from the filament, thus further tending to reduce shadows. As a further step toward the reduction of shadows, I may, instead of keeping the filament exactly parallel to the bulb axis, turn it to a slight angle, about ten degrees to a plane through said axis, keeping the middle of the filament in a plane through said axis.

As shown in Figure 2, the filament supports 4 and 15 and the filament 14, are all in one plane with the center of the filament supported by the wire 6 from the arbor button 7. This provides an easily assembled mount, and one which makes the lamp resistant to vibration or jarring. If the supporting wire went back directly to the stem, instead of being supported by the arbor, the whole filament supporting structure might vibrate easily and could be easily jarred out of place and out of focus. The filament is preferably placed half-way between the axis of the bulb and the reflecting surface.

The bulb is attached to a lamp base, 16, which may be of the usual screw type. In order that the reflector lamp may be capable of being turned in its socket through a considerable angle without breaking the circuit contacting with its terminals, a flexible extension contact 11 may be soldered or otherwise secured to the usual central contact of such a base, as shown for example in United States Patent 988,416, issued April 4, 1911, to M. H. Welsh. A small raised protuberance 13, may be placed on the screw threads at one or more places to insure that the base is held firmly in the socket while being turned.

The part of the lead-in wires inside the bulb may be of a soft nickel wire, while the central support wire 6, may be of a stiff molybdenum wire, and the filament of tungsten, to provide a rigid support which withstands vibration and jarring without harming the filament or shifting its position appreciably.

What we claim is:

In an electric incandescent reflector lamp, a tubular glass bulb of circular cross-section whose interior surface is lightly frosted to produce a smooth but narrow beam of light from the reflector, one end of said tubular bulb terminating in a hemispherical portion and the other end terminating in a reentrant stem, a metallic reflecting coating on part only of the interior frosted surface of said tubular bulb and extending around more than half of the circular cross-sectional circumference of said bulb, a coiled-coil tungsten wire filament arranged with its axis in a straight line parallel to the axis of the tubular bulb and approximately half-way between said bulb axis and the reflecting surface, lead-in wires sealed through the press of the stem,

the portion of said wire inside the bulb being of nickel, one of said wires extending directly into the bulb from the stem and having its end bent toward the coated portion of the bulb and supporting one end of the filament, the other of said wires being curved outward from the stem toward the coated portion of the bulb and having its end bent back away from the coated portion of the bulb to support the other end of the filament, a glass arbor extending from the press of the stem along the axis of the bulb and terminating in a glass button nearer to the stem than the axially perpendicular plane containing the nearest end of the filament, a stiff wire of smaller diameter than the lead-in wires sealed into said button and extending from it substantially parallel to the bulb axis but bent at the end to support the middle of the filament coil by being looped around it, and a filling within said bulb of gas inert with respect to said filament and to said metallic reflector coating.
